UNITED STATES PATENT OFFICE.

WILLIAM E. SEVERANCE, OF HOBOKEN, NEW JERSEY, ASSIGNOR OF ONE-HALF TO
DANIEL HARTLEY, OF NEWARK, NEW JERSEY.

LATHE.

1,139,235.

Specification of Letters Patent. Patented May 11, 1915.

Application filed September 24, 1913. Serial No. 791,506.

To all whom it may concern:

Be it known that I, WILLIAM E. SEVERANCE, a citizen of the United States, and a resident of Hoboken, in the county of Bergen and State of New Jersey, have invented 5 certain new and useful Improvements in Lathes, of which the following is a specification.

The improvements relate to lathes and 10 their objects are, among others, to so improve the construction and arrangement of the frame and movable parts as to render them simpler, more easily adjusted and capable of facilitating a great variety of work 15 with a relatively small number of tools, and to so construct and arrange the said parts that the lathe may be quickly and easily dismembered for shipping or other purposes and as easily assembled and set up for use. 20 The improvements consist in the construction, combination and arrangement of parts hereinafter described and claimed and illustrated in the accompanying drawings.

In the said drawings, Figure 1 is a side 25 elevation of a lathe embodying the improvements. Fig. 2 is a plan of the same. Fig. 3 is a vertical section of the tail-stock taken substantially on the line 3—3 of Fig. 1 and looking in the direction indicated by the arrows in that figure. Fig. 4 is a vertical section 30 of the slide-rest substantially on the line 4—4 of Fig. 1 looking in the direction indicated by the arrows in that figure. Fig. 5 is a vertical section taken substantially on the line 5—5 of Fig. 1 looking in the direction indicated by the arrows in that figure. 35

Instead of having the ordinary groove and clamp in which the slide-rest and tail-stock move to and from the head-stock a 40 pair of horizontal parallel bars A, A' are provided, and on these bars the parts mentioned—as well as other parts when desired—are slidably mounted by means of alined apertures in their bases through 45 which the bar A passes, and movement of the slidable parts in a vertical plane is prevented by the bar A' upon which the opposite side of the bases rest.

The bars A and A' are detachably mounted 50 in the standards B and C, by being passed through bored bosses B' and C' respectively in the upper part thereof and held therein by means of set screws B² and B³ in the former and C² and C³ in the lat-

ter. In order to strengthen the frame of 55 the lathe and give it the desired rigidity a third bar A² is passed through the posts or standards near the bottom of each and secured by means of set screws B⁴ and C⁴. This third bar is in a vertical plane midway 60 between the two upper bars and like the said upper bars may be removed when desired. The pulley D, mandrel E and head-stock are journaled in the crotch F of the standard B and are adapted to be driven by a suitable 65 belt. The slide-rest G and the tail-stock H are mounted to slide on the bar A, as above stated, and have extensions G' and H' of their bases resting on the bar A' opposite. These portions which rest upon the bar A' 70 are provided with adjusting screws G² and H² respectively whereby the said parts, and the tools carried thereby or resting thereon may be tilted or canted so as to be held in different positions radially with respect to 75 the center I (see Fig. 4), and in this manner the work on the tools may be controlled with the greatest accuracy and precision. The frame of the tail-stock is provided at 80 its rear end with a plate J which enters the groove K' of the internally threaded sleeve K, and the said plate J is held against the frame by means of a clamp L, so that the spindle M may be moved backward and forward through the sleeve H⁴ by means of 85 the screw M', or moved to an inoperative position by loosening the plate J and allowing it to drop from engagement with the said groove K'. The plate J is provided with a vertical slot J' which permits this 90 downward movement. Tools of various kinds may be inserted in the tail-stock and held therein by the set screw N. The slide-rest and tail-stock may be fixed in any desired position longitudinally of the bars A, 95 A' by means of the clamps G³, H³, and a stop O clamped on the bar A is also provided for the purpose of limiting the forward movement of the tool or other device carried by the slide-rest. 100

It will be seen that the bar A may be quickly removed from the standard B by releasing the set screws B² and C² and sliding it backward, and this provision enables the operator to quickly remove the slide-rest by 105 sliding it off the end of the bar and to replace it by another of any desired kind. The spindle M may also be moved to and

from the work by means of the lever P which has its fulcrum in the outer upturned end of the bracket R mounted in the tail-stock and movable laterally therethrough, but adapted to be fixed by means of the clamp S. The lever has a pin P² which enters a hole in the spindle, and its outer end has an open slot P' which permits the lever to be removed when not in use, this removal being facilitated by moving the bracket R outward so as to withdraw its upper end from the slot after which the pin may be removed from the hole of the spindle.

It will be apparent that a lathe constructed in accordance with the present improvements is capable of a variety of adjustments and that a great variety of work may be done by manipulation of the parts with relatively few tools. It will also be apparent that such a lathe possesses great advantages in that it is of simple, light and compact construction and may be quickly and easily dismembered and packed for shipping or other purposes and as easily assembled and set up for use. One of the advantages not hereinbefore specifically referred to is that resulting from the arrangement whereby the bottom plates of the clamps by which the parts mounted on the bars A and A' are secured may be turned so as to pass between the bars and the said parts then turned to a position in which they depend from the bar A and leave a space above the said bars free and unobstructed, while at the same time the said parts are not disconnected and may be quickly restored to their normal position. Other advantages will appear to those skilled in the art.

40 In the foregoing specification and in the claims various terms familiar to the art have been applied to some of the parts, as for instance "tail-stock," and "slide-rest." The parts referred to, however, differ in 45 many respects from those common in the art and are capable of performing functions not usually performed by the parts described by such terms. It must therefore be understood that these terms are used for 50 convenience of description and not with the intention of disclaiming any of the novel features.

What I claim is:

1. In a device of the character described, 55 the combination of a plurality of standards, a plurality of bars horizontally disposed mounted in said standards, a tail-stock mounted on said bars to have free movement vertically with respect to one of them, 60 and means for adjusting the limit of said movement.

2. In a device of the character described, 65 the combination of a plurality of standards, a plurality of bars horizontally disposed mounted in said standards, a slide-rest

mounted in said bars and freely slidable to and fro thereon and means for moving the said slide-rest vertically and for maintaining it in different positions thereon, said means permitting free vertical movement of 70 the rest in one direction.

3. In a device of the character described, the combination of a plurality of standards, a plurality of bars horizontally disposed detachably mounted in said standards, and 75 extending from one to the other, a tail-stock mounted on said bars to have horizontal movement thereon, and means for moving the said tail-stock vertically and for securing it in different vertical positions thereon. 80

4. In a device of the character described, the combination of a plurality of standards, a plurality of bars horizontally disposed one of which is detachably mounted in said standards, and extends from one to the 85 other, a tail-stock mounted on said bars and means for moving the said tail-stock vertically and for securing it in different vertical positions thereon.

5. In a device of the character described 90 the combination of suitable standards, a bar horizontally supported by said standards, a tool supporting member mounted to slide freely to and from the head on said bar, a second horizontal bar adjacent to the first 95 and adapted to receive and support a portion of the said tool supporting device, means for moving the said supported portion to and from the said last named bar and for holding the same in different positions with respect to said bar, said holding means permitting additional movement of the supporting device in one direction angular to the bar. 100

6. In a device of the character described 105 the combination of suitable standards, a bar horizontally supported by said standards, a tool supporting member mounted to slide on said bar, a second horizontal bar adjacent to the first and adapted to receive and support a portion of the said tool supporting device, means for moving the said supported portion to and from the said last named bar and for holding the same in different 110 positions with respect to said bar, means for clamping the said tool carrying device to the said bars, the said means being constructed and arranged to permit the said device when not clamped to move to a position substantially outside its normal working position. 115

7. In a device of the character described 120 the combination of suitable standards, a bar horizontally supported by said standards, a tool supporting member mounted to slide freely to and from the head on said bar and to oscillate thereon, a second horizontal bar adjacent to the first and adapted to receive and support a portion of the said tool supporting device, means for moving the said 125 130

supported portion to and from the said last named bar and for holding the same in different positions with respect to said bar.

8. A lathe consisting of a plurality of standards, a plurality of horizontally disposed bars removably mounted on said standards, and connecting the same, a head-stock and a spindle mounted to rotate therein in one of said standards, and a slide-rest 10 and tail-stock removably mounted on the said bars.

9. A lathe consisting of a plurality of standards, a plurality of horizontally disposed bars removably mounted on said 15 standards, and connecting the same, a head-stock mounted in one of said standards, and a slide-rest and tail-stock mounted on the said bars, the connection between one standard and the horizontal bars being such as to 20 permit the standards to be moved to and from each other without being removed from the bars and to be secured in different positions so as to produce in effect a lathe frame of different lengths.

25 10. In a device of the character described, a tail-stock mounted to move horizontally, means for mounting a tool in a portion of said tail-stock, a connection between the said portion of the tail-stock and the tail-stock 30 proper permitting independent movement of the former, and means for moving the same to and from the head comprising an arm adjustable angularly to the line of movement of the said tail-stock, a lever 35 mounted on said arm and a connection between the lever and the portion of the tail-stock in which the tool is mounted, said connection being such that the movement of the arm at an angle to the line of movement of 40 the tail-stock disconnects it from the lever.

11. A lathe consisting of a plurality of standards, a plurality of horizontally disposed bars removably mounted on said standards connecting the same and forming 45 an intermediate structure, connections between said bars and one of the standards permitting the said standard to be moved along said bars to and from the opposite standard, and a tool holding device removably mounted on said bars intermediate said standards and adapted to slide thereon.

50 12. A lathe consisting of a plurality of

standards, three bars horizontally mounted in said standards, two of said bars being out of horizontal and vertical plane with each other, a tool holding device mounted on one of said bars and adapted to oscillate thereon as a pivot, and means whereby the said tool holding device is supported on another of said bars to have free movement to and from the same, said means being adjustable to limit the said to and from movement at different points.

13. A lathe consisting of a plurality of standards, a plurality of horizontally disposed bars removably mounted on said standards connecting the same and forming an intermediate structure, connections between said bars and one of the standards permitting the said standard to be moved 65 along said bars to and from the opposite standard, and a tool holding device removably mounted on said bars intermediate said standards and adapted to slide thereon, and means for supporting the said tool holding 70 device on one of said bars without attaching the same thereto, said means including an adjusting member for gaging the elevation 75 of the member with respect to the bar but permitting free movement thereof in one direction.

14. A lathe consisting of a plurality of standards, a plurality of horizontally disposed bars removably mounted on said standards connecting the same and forming 85 an intermediate structure, connections between said bars and one of the standards permitting the said standard to be moved along said bars to and from the opposite standard, and a tool holding device removably mounted on said bars intermediate said standards and adapted to slide thereon, a 90 pivotal connection between the said tool holding device and one of said bars and means whereby it is supported without being connected to the other bar.

Witness my hand this 19th day of September, 1913, at the city of New York, in the county and State of New York.

WILLIAM E. SEVERANCE.
